UNITED STATES PATENT OFFICE

1,984,276

DISTRIBUTOR

Marion Mallory, Detroit, Mich., assignor to
 Mallory Research Company, Toledo, Ohio, a
 corporation of Delaware

Application June 12, 1933, Serial No. 675,387

2 Claims. (Cl. 200—21)

The chief object of this invention is to reduce the interference with a radio set installed on a car, created by the ordinary high tension distributor.

- 5 Normally, the distributor rotor has a radial clearance of $1/64''$, which, in actual practice, is variable so that sometimes it is nothing and again it may be $3/16''$, depending on the eccentricity of the rotor.
- 10 If the high tension terminals are made flush with the surface of the roof of the distributor, then the rotor rubbing against the terminals picks up particles of metal, which scratch the insulation of the roof between the terminals, and eventually irregular arcs are formed as before, which arcs set up disturbances which influence the aerial on the car and interfere with radio reception.

If the contact could be brought to and maintained at a constant minimum distance, then the 20 irregular arcs would never be formed and the disturbance originating in the distributor could be greatly lessened.

In the drawings:—

Figure 1 is a cross-sectional elevation taken 25 on the plane 1—1 of Figure 2.

Figure 2 is a plan view looking up on the plane 2—2 of Figure 1.

Figures 3 and 4, corresponding with Figures 1 and 2, show an alternative construction.

30 Figures 5 and 6 show another alternative construction.

Figures 7 and 8 show another alternative construction.

Figures 9, 10 and 11 show another alternative 35 construction.

In the figures:—

10 is the main high tension central lead which admits the high tension current for distribution by the distributor. 11 and 12 are two of the high 40 tension leads, leading out of the distributor to the spark plugs (not shown). 15 is a cap screw, holding the cap 14 to the rubber pad 13 in which the leads are securely held. This rubber pad is crushed against the roof 16 of the distributor, so as to tightly grasp the leads 10, 11 and 12. In the 45 roof 16 of the distributor is a rail 17 against which rides a metal disc 33, carried by the rotor 32, in a well known manner. The high tension wires 10, 11 and 12 terminate at the high tension terminals 18, 19 and 20. The central terminal 20 is in contact with the metal strip on top of the rotor 32, and thus is electrically connected with the metal disc 33. The other two terminals 18 and 19 project from the roof so as to be almost, but 50 not quite flush with the upper surface of the rail

17. The rotor 32 is rotated by the cam shaft 29 through the cam 30. A breaker mechanism 31 is shown by means of which the primary circuit is made and broken. The roof 16 is supported by a cylindrical portion 47 (which is connected to the base 34 by the spring clamp 26), in which rotates the drive shaft 27 and disc 28, between which and the shaft 29 is located a centrifugal governor (not shown).

5 It will be noted that the high tension terminals 18, 21 and 24 in Fig. 2 are located on the outside of the rail 17, and the high tension terminals 19, 22 and 23 are located on the inside of the rail. The burning away or arcing on the disc 33 is thus balanced.

10 In Figure 3, the terminals 18, 19 etc. are located in a groove formed between the rail 17 and the outer casing 47. The disc 33 is thus allowed to ride on the shelf in which the groove is formed.

15 In Figures 5 and 6, the disc rides on a rail 17, but, in this case, the terminals 18 and 19 are all located on the inside of the rail, and not alternatively on both sides as in Figures 1 and 2.

20 In Figures 7 and 8, the high tension terminals 18 and 19 are arranged in a groove formed between the double rail 17.

25 In Figures 9, 10 and 11, the electrodes 18, 19 etc. are arranged in recesses in a shelf 17 formed on the side of the cover 47. These recesses are connected by a shallow groove, which has a width 30 equal to that of the high tension terminal 18, so that any pitting or building up that takes place on the face of the disc 33, due to arcing, will not scratch that portion of 17 of the rail 35 upon which the disc 33 slides.

When the outer terminals are arranged, as in 40 Figures 1 and 2, so that the rail constitutes a barrier or partition between successive terminals, this prevents a spark from starting at the base of one of these terminals and traveling along the surface of the bakelite to the next terminal. That is, the path is made sufficiently longer by the interposition of the partition to force the 45 spark to jump at the top of the terminal. Jumping of the spark in this manner is also substantially prevented by the formation of notches or recesses in the rail 17 in the vicinity of the terminals, as shown more particularly in Figure 10, thereby increasing the air gap between the rail and the end of the terminal, because a spark 50 will travel with appreciably less resistance along a surface than across an air gap, even though the surface is formed by a good insulating material.

55 Another disadvantage of not having a relief

around the terminal is that the rotor, if it is spring loaded, will tend to rebound and dig into the charred area on the trailing side of the terminal. If the edge of the rotor blade is sharp or square, some of the wearings from the metal will often become embedded in the charred portion of the track. If there is an air gap around the terminal, there can be no burning of the bakelite around the trailing side thereof, and 10 the attendant troubles are avoided.

Any normal particles of wear, especially of the metal rotor blade, are wiped into the circular relief or into the groove instead of being embedded in the track. Several attempts have been 15 made in the past to use a wiping type of rotor with terminals set in a smooth bakelite surface, but it gave so much trouble in production that it had to be abandoned for the conventional jump type of high tension distributor. Metal particles 20 would become embedded in the track and would in time cause the spark to jump across to an adjacent terminal.

This application is a continuation in part of my application Serial No. 671,667, filed May 18th, 25 1933, "Distributors".

What I claim is:—

1. In a distributor, the combination with a 5 rotor having a metal blade thereon, of a housing provided with a roof of insulating material, a central terminal constantly connected to said blade, and a plurality of successive outer terminals adjacent the path of the outer end of said blade, said roof being formed with a rail, over the surface of which the blade rides, said rail being arranged to constitute a partition of insulating material between successive outer terminals. 10

2. In a distributor, the combination with a 15 rotor having a metal blade thereon, of a housing provided with a roof of insulating material, a central terminal constantly connected to said blade, and a plurality of successive outer terminals adjacent the path of the outer end of said blade, the inside of said roof being formed with a raised surface, along which the outer end of 20 said blade rides, said raised surface constituting a partition between successive outer terminals. 20

MARION MALLORY.
